UNITED STATES PATENT OFFICE.

HENRY CHENAULT, OF ALLENSTVILLE, KENTUCKY.

THILL-COUPING.

1,245,681.

Specification of Letters Patent.

Patented Nov. 6, 1917.

Application filed April 12, 1917. Serial No. 161,470.

To all whom it may concern:

Be it known that I, HENRY CHENAULT, a citizen of the United States, residing at Allensville, in the county of Todd, State of Kentucky, have invented a new and useful Thill-Coupling; and I do hereby declare the following to be a full, clear, and exact description of the invention, such as will enable others skilled in the art to which it applies to make and use the same.

This invention relates to an improved thill coupling between the thills of the shafts and the front axle of a running gear, and an object of the invention is to provide a simple, efficient and practical coupling, which may be manufactured at a small cost and sold for a reasonable profit.

A further object of the invention is to provide a coupling of this kind consisting of three parts, two of which are adapted to be clamped to the axle by the third part, which in turn pivotally clamps a loop of the thill plate or bar to the coupling.

A further object of the invention is to provide the third part of the coupling with bolts extending through the clamping parts on the axle, and one of said bolts is designed to pass through the axle, in combination with means on the third part to guide the same into clamping engagement with its attendant part.

In practical fields, the details of construction may necessitate alterations falling within the scope of what is claimed.

The invention comprises further features and combination of parts, as hereinafter set forth, shown in the drawings, and claimed.

In the drawings:—

Figure 1 is a view of the improved thill coupling, as applied to the thill and the axle of the running gear, which axle is shown in section.

Fig. 2 is a sectional view on line 2—2 of Fig. 1.

Fig. 3 is a vertical sectional view through the thill coupling, showing a portion of the thill iron or plate in elevation and partly in section.

Fig. 4 is a plan view partly in section on line 4—4 of Fig. 1.

Fig. 5 is a detail perspective view of the part of the thill coupling for pivotally connecting the loop of the thill iron to the coupling.

Referring more especially to the drawings, 1 designates an axle of the running

gear of a vehicle, and 2 the axle bolster which engages on the top of the axle. The coupling comprises the three parts 3, 4 and 5. The part 3 is in the form of a plate, the lower portion of which is provided with a right angle extending flange 6, which is provided with a downwardly extending lug 7. The upper part of the plate 3 is constructed with a curved portion 8, which overlies and engages the upper curved surface 9 of the axle bolster. The body of the plate 3 has an aperture 10. Formed transversely of the flange 6 and adjoining the lug 7 is an aperture or opening 11. The part 4 of the coupling comprises a body 12, with which is formed a plate 13. The lower portion of the plate 13 has a right angle extending flange 14 engaging under the axle 1 in opposition to the flange 6, and on the under surface of the flange 14 intermediate its ends is a lug 15, which, as shown merges into the body 12. The upper part of the plate 13 has a curved portion 16 overlying and engaging the upper curved surface of the axle bolster in a position opposite the curved portion of the plate 3. By this construction of the plates 3 and 13, the axle bolster is held more secure on the axle. The upper part of the body 12 has a T-shaped dove tail slot or opening 17, the inner portion of which adjoins a cylindrical opening 18. The lower part of the body 12 is provided with a similar T-shaped dove tail guide opening 19, which merges into a cylindrical opening 20 which extends through the flange 14 and its adjoining lug 15. The part 5 of the coupling is in the form of a clamping body, the inner face of which is V-shaped as shown in dotted lines in Fig. 4, and as also shown in Fig. 5. This V-shaped face of the clamping body 5 engages a similar shaped face of the body 12. The adjacent faces of the two bodies 5 and 12 are supplied with transversely disposed recesses 21 and 22, which are semi-circular in cross section, and the walls of these recesses toward their outer ends diverge or flare outwardly, as shown in Fig. 4 clearly, thereby permitting looseness of play of a pivot pin or bar, which is designed to engage said recesses. The upper and lower parts of the V-shaped face 23 of the body 5 are provided with T-shaped dove tail projections 24, to engage the T-shaped dove tail openings 17 and 19. The projections 24 have cylindrical extensions or bolts 25, which extend through the openings 10 and

110

11, 18 and 20. The upper bolt 25 extends through the axle bolster, as shown at 26. The rear ends of said bolts 25 have nuts 27 threaded thereon, which when tightly 5 screwed home, draw the adjacent faces of the clamping bodies 5 and 12 together, and at the same time clamp the plates 13 and 3 to the forward and rear faces of the bolster and the axle respectively. The inner face of 10 the clamping body 5 adjacent the projections 24 is provided with tapering lugs 28 which enter similar bores 29 of the body 12, thereby more firmly holding the clamping body 5 in place. A suitable thill iron 30 (which is 15 secured to a shaft 32 by means of the bolts 31) is provided, and the rear lower end of the iron terminates in a loop 33. The transverse portion 34 of the loop 33 constitutes a pivot pin, the opposite ends of which are 20 larger in diameter than its central portion. In other words, the pin 34 tapers from its opposite ends toward its center and is fulcrumed in the opposing recesses 21 and 22 of the bodies 5 and 12 in such wise as to afford 25 a slight lateral looseness of play for the thill iron, yet permitting the thill iron to pivot vertically. The outer surfaces of the plates 3 and 13, respectively, are provided with grooves 35 and 36, which are designed to receive 30 suitable clamping straps, (not shown) of a running gear (not shown).

The invention having been set forth, what is claimed as new and useful, is:—

1. In a thill coupling, a pair of clamping 35 plates engaging the forward and rear surfaces respectively of an axle and its bolster, an axle and a superimposed bolster between said plates, a thill iron provided with a loop having a transverse pivot pin forming an 40 integral part of the loop, a clamping body provided with integral projections passing through said plates and having means threaded thereon to hold said parts together, said clamping body and one of the adjacent 45 plates having tapering adjoining recesses in which the pivot pin of the loop is mounted to have looseness of play therein.

Copies of this patent may be obtained for five cents each, by addressing the "Commissioner of Patents, Washington, D. C."

2. In a thill coupling, the combination of an axle and a superimposed axle bolster, of 50 clamping plates engaging the forward and rear faces respectively of the axle and bolster, one of said plates having a body, a clamping body engaging the first body, both bodies having adjoining engaging V-shaped faces, the V-shaped face of the 55 clamping body having threaded projections passing through said plates, one through the axle bolster, means engaging the threads of the projection to clamp the parts together, a thill iron having a loop provided 60 with a transverse pivot pin portion pivotally mounted between the adjacent faces of both bodies.

3. In a thill coupling, the combination of an axle and superimposed axle bolster, of 65 a pair of plates engaging the forward and rear faces, respectively, of said axle and its bolster, said plates having upper and lower flanges overlying the upper and lower portions respectively of the bolster and said 70 axle, one of said plates having a body, a thill iron having a loop provided with an integral transversely disposed pivot pin which tapers from the outer end toward the center, a clamping body engaging the 75 forward face of the first body and provided with projections having their rear ends threaded, nuts on said ends to clamp the parts together, the adjacent faces of the two bodies having adjoining recesses substantially conforming in shape with and receiving said pivot pin of the thill loop, in order to permit lateral looseness of play of the thill iron as a vertical pivotal movement, and means for reinforcing the clamp- 80 ing connection of the two bodies.

In testimony whereof I have signed my name to this specification in the presence of two subscribing witnesses.

HENRY CHENAULT.
